(57) **CLAIM**

The ornamental design for a roofing support system, as shown and described.

DESCRIPTION

FIG. 1 is a perspective view of a second embodiment of a selectively attachable/detachable roofing support system comprising an upper core member comprising a substantially rigid molded polymer and having integral right side and left side pockets comprising handles or grips, in a detached condition;

FIG. 2 is a bottom perspective view thereof;

FIG. 3 is a top view thereof;

FIG. 4 is a bottom view thereof;

FIG. 5 is a left side view thereof;

FIG. 6 is a right side rear view thereof;

FIG. 7 is a front view thereof; and,

FIG. 8 is a rear view thereof.

1 Claim, 6 Drawing Sheets
